UNITED STATES PATENT OFFICE.

WILLIAM E. SOMERVILLE, OF COAL CITY, ILLINOIS.

FLYING-MACHINE.

1,185,728

Specification of Letters Patent.

Patented June 6, 1916.

Application filed March 17, 1913. Serial No. 754,999.

To all whom it may concern:

Be it known that I, WILLIAM E. SOMERVILLE, a citizen of the United States, residing at Coal City, in the county of Grundy 5 and State of Illinois, have invented new and useful Improvements in Flying-Machines, of which the following is a full, clear, concise, and exact description, reference being had to the accompanying drawing, forming a 10 part of this specification.

My invention relates to improvements in flying machines with especial reference to those having a multiple of planes, and has for its object the production of a machine 15 formed from a multiple of units that can be readily assembled and disassembled without it being necessary to loosen the connecting wires.

A further object is the production of a 20 machine formed of a series of detachable parts and means whereby said parts may be detached and knocked down, and caused to occupy small space.

A further object is the production of a 25 machine of simple, yet efficient construction that can be cheaply manufactured and one not liable to disarrangement of parts.

These and such other objects as may hereinafter appear are attained by my device, 30 embodiments of which are illustrated in the accompanying drawings, in which—

Figure 1 represents a perspective view of my completed machine. Fig. 2 represents a detail sectional front elevation showing a 35 portion of the center and one side of my device. Fig. 3 represents a sectional side elevation of my device. Figs. 4 and 5 represent enlarged detail views showing method of securing the parts together. Figs. 6 and 40 7 represent enlarged sectional views showing modified means of securing the parts together.

Like numerals of reference indicate like parts in the several figures of the drawing.

Referring now to Fig. 1 which shows my 45 invention as embodied in a biplane, A represents the top plane terminating in upturned ends B and having an upright central fin C, the wings being rigid and connected with the body of the plane by means of wires b, the upturned fin also being rigid

and connected with the body of the plane by means of wires c. D represents the lower plane, E the chassis containing the operator and mechanism and engine F. G 55 represents the tail extension secured to the chassis at its front end and terminating at its rear end in a horizontal tail plane H, provided with movable elevators h operable by means of wires h' extending from the 60 rear of the movable planes over posts I to the operator. Vertically mounted between the elevators h is the rudder J. The machine as a whole is mounted on the usual carriage K and provided with wheels L. 65 In this machine I have illustrated a machine similar to that heretofore invented by me and fully described in my application for Letters Patent filed November 4th, 1910, and no claim is made herein for the device 70 heretofore described. The planes A and D are formed of any desired material spread over a hollow frame-work as is common in machines of this kind, but is made up of a series of sections d, each section being independently wired and secured to the edges of the adjacent section in such a manner that it may be possible to separate the sections 75 without disconnecting the individual guys extending from the top plane to the bottom 80 plane.

Referring now to the individual sections d shown in longitudinal cross-sections in Figs. 2 and 3, it will be noted that each individual section comprises top planes M and 85 bottom planes M', each plane having parallel bars N and N' connected by means of cross-rods n. Above and below these cross-bars N and N' are secured a series of ribs O O held together at the front and rear by 90 rods or bars P. Spacing members Q Q are placed between the ribs to separate them apart and give them the proper curvature, and over the entire structure thus formed is stretched covering material of silk or duck 95 as shown in Fig. 1.

Referring now to Fig. 2, adjacent end members N N' are connected together by means of strap hinges R R through the eyes of which are passed bolts R', a similar construction being used both above and below the bars and on the top and bottom plane.

Angle bars S are also secured to the bottom side of the upper bars N and the upper side of the lower bars as shown at S', these bars being spaced apart to permit the insertion of a post T therebetween, the post holding the upper and lower planes in operative position.

5 Retaining pins or bolts s s extend through holes in the vertical leg of the angle iron and are adapted to enter in corresponding openings in the post T, both below the upper bar and above the lower bar. The post itself is preferably jointed or hinged as shown at t and a collar T' surrounds the 10 post and holds the same rigid. Retaining lugs or ears U U are mounted on the under-side of the upper bar and the upper side of the lower bar adjacent the posts and stiffening wires w w are extended diagonally from 15 one to the other, thus making a rigid structure, tighteners w' being interposed in each guy wire.

In Fig. 7 I have shown a modification in which a single hinge V is employed and 20 an upwardly curved plate preferably formed with an upwardly extending ear v taking the place of the angle iron S S' shown in Fig. 2, the guy wire w being connected directly to the upturned end of the member V. In Fig. 6 a sectional view of the form 25 illustrated in Fig. 7 is shown in which the post itself is also provided with a single hinge W surrounded by a collar T', a stop X being set into the posts to limit the downward movement of the collar T'. The upturned ends B are also secured to the adjacent end plane so that they may be removed from the structure in the same manner as the planes are separated one from the other. 30 The reason why it may be advisable to have different forms of fastenings securing the sections together is that in some of the types of machines the main bars on which the planes are built up are entirely hidden within 35 the structure as shown in Fig. 3 or may be at the front and back of the structure as shown in Fig. 7.

Suppose now that the plane is assembled, and it is desired to knock it down for shipment. It is only necessary to slide the collars T' from over the joint permitting the posts or braces T to bend, thus relieving the tension on the guy wires. The bolts R' are then slipped from the eyes of the 45 hinges, thus entirely disconnecting one bar from the other, as shown at the right hand of the drawing in Fig. 2. The parts may then be separated by pulling them apart, the bolts s slipping out of the sockets in 50 the post but remaining in the angle iron S. The upper and the lower members may then be brought together one on top of the other, the wires being loosely disposed between the planes. The posts may then be packed 55 separately and all of the plane members be

caused to occupy a very small space compared with that in set up condition.

In place of the bolt s its equivalent may be used in the shape of an integral projection or lug on the bars S adapted to fit into the 60 post.

No specific claim is made to the particular means of securing the parts together as it is evident that any of the well known means of removable uniting members can 65 be utilized without departing from the spirit of my invention.

In view of the great number of fatalities accompanying the use of the mono-plane, the bi-plane has become the standard machine in most instances and the question of transporting the machine from place to place by other than its own power has become a serious problem. Heretofore, the only way in which the machine could be 70 knocked down for shipment was to loosen up and disconnect a great part of the guy wires and disconnect the planes, which were generally integral, from the structure, the planes themselves never being in more than 75 two parts, one on either side of the center of the structure, and being very bulky took up a large space in transportation. By the use of my device, however, it is seen that the machine, so far as its planes are concerned, 80 may be quickly and efficiently disassembled or knocked down and caused to occupy a comparatively small space, and yet may be as quickly put together and be brought into 85 co-operative relation with the machine as a 90 whole, it being simply necessary to raise the two adjacent upper plane members together, at the same time slipping the posts, slightly bent, into position, locking the members together both above and below by means of 95 the bolts R' then straightening the posts and slipping the collars T' over the joints, thus stiffening the entire structure and making the two planes integral. Of course, it is 100 understood that the lower planes are to be placed close together before lifting the upper planes so that the lower end of the posts may be fitted in place the same as the upper end and at the same time.

The ability to quickly assemble and disassemble machines of this character which heretofore have taken one-half a day to a day to assemble becomes a very important feature especially in operations of war making it possible, when it is not desired to 105 operate the machine by its own power from place to place to knock it down and set it up again in a very short space of time.

I claim:

In a flying machine the combination with 1 a sectional upper plane, a sectional lower plane, removable means for securing said sections together, hinged posts adapted to be fitted between the ends of corresponding upper and lower sections, removable means 1

for making said posts rigid, a series of guy wires contained between corresponding upper and lower sections, and a pair of upwardly extending sections removably secured to the outermost upper section on each side of the machine.

5 In witness whereof, I have hereunto sub-

scribed my name in the presence of two witnesses.

WILLIAM E. SOMERVILLE.
